UNITED STATES PATENT OFFICE.

SYLVANUS ALBERT REED, OF NEW YORK, N. Y., ASSIGNOR TO THE REED PROPELLER CO., INC., OF NEW YORK, N. Y., A CORPORATION OF NEW YORK.

AERONAUTICAL PROPELLER.

Application filed June 22, 1922. Serial No. 570,139.

To all whom it may concern:

Be it known that I, SYLVANUS ALBERT REED, a citizen of the United States, and resident of New York, in the county of New York and State of New York, have invented certain new and useful Improvements in Aeronautical Propellers, of which the following is a specification.

This invention relates generally to propellers for aeronautical use and particularly to propellers of the metal type.

In my Patent No. 1,463,556, granted July 31, 1923, I have described and claimed a new and improved type of aeronautical propeller which includes among other features the use of metal as a material from which to form the propeller. The main reason indicated in said patent for specifying metal depended upon the fact that, as the 20 superiority of the propeller disclosed was due mainly to its thin sharp blades, especially in their outer and more rapidly moving portions, and as such thinness would be relatively devoid of structural or 25 intrinsic rigidity, the invention therein described included the making of the propeller of metal and relying largely upon centrifugal force to supply the necessary resistance to flexure. With such thinness and 30 flexibility of the outer portions of the blades, was associated an increase in cross-section and corresponding intrinsic rigidity progressively towards the axis of rotation. The increase in the present invention in 35 cross-section being so proportioned at various parts that, while still maintaining a relative thinness of the inner sections, the outer and more flexible portions are supported and maintained in operative angles 40 and positions for the necessary thrust, in conjunction with the use of a light-weight metal of high tensile strength as being especially adapted to such purpose.

The effect of centrifugal force, while 45 favorable to resistance of the blade to forward and tangential flexure under the influence of air resistance, may be unfavorable to permanence of the longitudinal twist given to the blades to give them the desired 50 helical pitch, and to maintain this twist constant, the intrinsic rigidity of the blade must be sufficient to resist the influence of

air resistance. While the centrifugal force is sufficient to supply the necessary rigidity against axial and tangential flexure to the 55 thin sharp outer portions of the blades, yet the rigidity of the blades against change of pitch is maintained, there is needed a correct adjustment of the weight of material to dimensions and form at the successive 60 blade cross-sections. When using a heavy metal this is difficult unless the blades are made hollow, which is objectionable and has not proved satisfactory in practice. When solid, the blades must, with heavy 65 metal, be made of a thinness graduated at all sections which though possible of adjustment to flying conditions is close to the border line of practicability. Reference was made in my said patent to the use of 70 aluminum, a light-weight metal, as a factor in obtaining the desired lightness of construction, and the present application, which is in large part a division or continuation of said patent, particularly includes, among other features, a propeller 75 formed of relatively light-weight metal of sufficient strength.

I have discovered that an alloy of aluminum which is nearly as light as the latter and which has in addition physical properties similar to steel, possesses the qualities which enable me to give to the relatively thin blades a sufficient thickness to furnish structural rigidity with an ample margin 80 to support the pitch twist at a constant figure, and yet not reach a prohibitive weight, while at the same time affording enough centrifugal force to provide kinetic 85 or virtual rigidity to the outer parts of the blades sufficient to minimize flexure and still preserve the thinness and sharpness which is an important feature of the invention. I, therefore, prefer to use alloys of 90 this character, such as duralumin or even 95 lighter alloys of other metals provided they have similar physical properties and are sufficiently elastic and non-brittle, also malleable and flexible, and have the necessary tensile strength. With such physical properties and a weight not exceeding $\frac{1}{8}$ of a pound per cubic inch, I am able to make 100 solid propellers with an ample margin between the limits of bulk and weight to

operate with superior efficiency and yet not exceed, or substantially exceed, the weight of a wooden propeller for the same service.

5 My propeller is made of a light and strong metal and preferably in a single piece and without hollow spaces, welds, rivets or joints, and is not only of superior efficiency in that it makes possible the use 10 of thin sharp blades, but is superior to wooden propellers and hollow metal propellers in permanence and resistance to wear and tear of service.

In my said patent hereinbefore referred 15 to, I have obtained the central reversal of blade angle by a compound bend equivalent to a twist of the flat plate from which the propeller was formed and I used shaft-attaching blocks, shaped to the contour of 20 the central bends which had as one function to assist in maintaining the blade against straightening out under the pull of centrifugal force. I have discovered that with proper dimensions, shape and character of 25 material of the propeller, such as the aluminum or similar alloys mentioned, the shaft-attaching blocks may be dispensed with and the set or rigidity of the material may be relied upon to maintain the central 30 bends or twists constant, so that for attachment to the driving-shaft only a flange at the end of the shaft is necessary and to which the propeller is screwed or bolted, or otherwise attached. Such flange may be 35 of varying form and either integral with the shaft or attached thereto by a sleeve or tubular extension keyed to the shaft, and the flange may be flat with filler-blocks interposed to fit the curved contour of the 40 propeller, or the flange may be itself curved to so fit the propeller contour.

It is to be noted that the relatively wide and relatively thin central region of my propeller affords the maximum efficiency for 45 transmission of the torque of the drive-shaft relatively to the mass of material. I have also found that the central reversal of blade angle can be safely made by a simple twist of the wide flat central zone of the propeller, and I prefer such simple twist, as it 50 brings the working or useful region of the blade closer in towards the axis of rotation and thereby lengthens the operative blade surface. Such twist may be made while the 55 metal is cold and the resultant blade angles varied at will, by again twisting to a permanent set, and with the aluminum alloy mentioned, this may be done many times without weakening the blades.

60 In my said patent, I also describe a one-piece hub-less propeller of resilient metal having the blades integral with each other, and with the main part of each blade shown as substantially of uniform width, that is to say, with the leading and the trailing

edges of the blade parallel for the greater part of the length of the blade. As this prolonged parallelism of the blade edges is less favorable to the desired inter-relation of cross-sections before referred to, I avoid this 70 by making the blade of a tapering formation in both thickness and width starting from or near the central region of the structure and running to the blade-tip.

Like the form of blade in my said patent 75 the present form tapers in thickness from at or near the central part of the propeller to the blade-tip, and this characterizes the present form with the peculiarity of having something of a proportioned and inter-related taper in width and thickness.

I have found from actual flights of airplanes equipped with propellers embodying my inventions, that an efficient speed of propeller rotation can be attained far beyond 80 the velocity of rotation of propellers heretofore known which required the gearing down of the engine speeds to suit these restricted capabilities. I am, therefore, able to effectively utilize speeds in which the 85 tip velocities of the propeller are equal to and even greater than the velocity of sound, with corresponding efficiencies and other 90 advantages resulting therefrom.

Certain forms of my improved propeller 95 and certain preferred methods of constructing the same are hereinafter described and set forth and illustrated in the drawings; wherein:

Fig. 1, is a side view of a propeller embodying my invention.

Fig. 2, is a front view of the propeller shown in Fig. 1.

Fig. 3, is a central longitudinal section of the propeller shown in Figs. 1 and 2, with 105 shaft-attaching means added thereto.

Fig. 4, is a series of cross-sectional views taken on planes at different points of the length of the propeller.

Fig. 5, is a side view of the central portion 110 of the propeller, with a shaft passing through the same and a shaft-attaching device mounted in place.

Fig. 6, is a side view of a portion of the shaft, an attaching device for securing 115 the propeller to the shaft, the device being shown with a flange shaped to conform to the contacting face of the propeller.

Fig. 7, is a side view of the central portion 120 of the propeller and a portion of the shaft, with an attaching device having a conforming flange placed on opposite sides of the propeller.

Fig. 8, is a similar view to Fig. 1, of a 125 modified form of propeller.

Fig. 9, is a front view of the propeller shown in Fig. 8, together with the shaft attaching device.

Figs. 10 and 11, show side views of the 130 central part of propellers shown in Figs.

8 and 9, and also attaching means in modified forms.

Referring to the drawings, in Figs. 1 to 4, is shown a propeller formed of a single piece of metal, with tips 5 and 6 having a thickness of one-fourth to one-eighth of an inch or less, and 7 to 8 being central attaching region of angle reversal and having a thickness of about one half to one inch, the thickness of each blade tapering from said central part 7-8, to the tips 5 and 6. The width of the blades also preferably decreases from the central part 7-8, to the tips 5 and 6, respectively. 9 denotes a simple twist of the center part 7-8, to bring the section at 7, to an angle with the section at 8, usually of about ninety degrees. From 7 to 5 and from 8 to 6, the blades are then twisted each in the opposite direction from the first twist, so that the angle of the various sections indicated at *a*, *b*, *c*, *e*, *f*, and *g*, in Fig. 4, with the plane of the propeller rotation, or radial plane, diminishes towards the tips more or less in accordance with the well known helical law for the pitch desired. At each of the sections *a*, *b*, *c*, *e*, *f*, and *g*, the forward face is curved and the rear face more or less flat, and both edges of the blades are sharp. The sections at *c*, and *e*, are nearly flat on both sides and are sharpened at the edges and the section at *d*, is flat with rounded edges. A hole 10, is formed at the center of the part 7-8, of the propeller for receiving the drive-shaft 11, to which the propeller is securely attached by means of a tubular member 12, having a peripheral outwardly extending flange 13, for engaging the face of the propeller. The attaching flange is provided with a set of bolt-holes 14, which register with a corresponding set of holes 15, in the propeller, and suitable bolts 16, are placed through the registering holes for binding the parts together. While I show in Figs. 1 to 7, only two bolt-holes for securing the parts together, of course, more bolt-holes may be used. A suitable key 17, is used for locking the shaft and the tubular member 12, together, and takes into keyways formed in said respective parts, and the usual nut arrangement may be used to retain the propeller from moving forward on the drive-shaft. The attaching flange 13, may be flat and non-conformed to the contacting face of the propeller, as shown in Fig. 5, but I prefer to shape its contacting surface so as to completely conform to fit the face of the propeller, as shown in Figs. 6 and 7, and thereby make a close and reinforcing contact with the central part of the propeller and the blades, the said flange being preferably elongated in the direction of length of the propeller, in the forms shown in Figs. 1 to 7. In the

construction of the non-conformed flange 13, shown in Fig. 5, the space between the two surfaces is that of a flat surface against a curved one, and the bolts are relied upon to hold the parts in fixed relation. In this arrangement it is evident that the only function of this device is to transmit the torsion of the drive-shaft to the propeller in an efficient manner.

In Figs. 8, 9, 10, 11, I show a variation in the construction of the propeller in which a virtual twist in the central part 7-8, for bringing the sections at those points to the required angle with the plane of rotation, is accomplished by a compound bend at 18-19, and 20-21, these bends being in opposite directions and at angles 18 with 19, and 20 with 21, and each extending entirely across the propeller and the pair 18-19, being symmetrical with the pair 20-21. There are various combinations of bends which will accomplish the same purpose, but I prefer that substantially of the type illustrated, as it leaves a desirable flat portion 22, at the center in the plane of rotation and which is especially convenient and efficient for securing the propeller in operative position to its seat or attaching flange.

In this modification, the portion of the blades 7-5, and 8-6, has the same twist, contour, edges and dimensions as in the case of the other form, and there is likewise preferably a continuation of the leading edge of each blade with the trailing edge of the other.

In Figs. 8 to 11, the attaching means for securing the propeller in operative position in connection with the drive-shaft 11, are shown in modified forms. In Figs. 8 to 10, the tubular attaching member 12, has an annular attaching flange 13, the device being the same as that previously described, except the flange is circular, instead of oblong, and has a circle of bolt-holes 14, corresponding with a similar series of bolt-holes formed in the flat part 22, of the propeller and which register with each other and receive the attaching bolts 16. In Figs. 8 and 9, this unitary device with its bolts is all that is used, while in the construction shown in Fig. 10, there is added upon the opposite side of the propeller, a clamping disk 23, having a central perforation for the shaft and a circular row of bolt-holes for receiving the attaching bolts 16, which pass through corresponding holes in the propeller and the flange 13. The key 17, which is set in a keyway in the shaft and also in the flanged-tube 12, also takes into a keyway in the central perforation of the clamping-disk 23.

In Fig. 11, I show the use of shaft attaching parts ordinarily used in mounting wooden propellers and which comprise a

metal disk 24, like the disk 23, in Fig. 10, which engages one face of the propeller, a second clamping disk 25, upon the opposite side of the propeller with a central orifice 6 to receive the shaft and bolt-holes for receiving the bolts 16, a block of metal or other material 26, being interposed between the disk 25, and the flat section 22, of the propeller, with the shaft 11, passing through 10 said block, and the bolts 16, also extending through the same. This arrangement permits the use of my improved propeller with the attaching devices or hubs already in use so that the same may be used and a saving 15 thereby made in the expense of the mechanism.

It is evident that in none of the arrangements described in reference to Figs 8, 9, 10, and 11, is the attaching means required to 20 reinforce the twist or bend in the propeller, but functions merely as an attaching means to the drive-shaft embracing the latter over sufficient of its length to allow adequate keying of the parts. The twist or bend of the 25 metal or other material imparted during manufacture of the propeller, for the purpose of giving the blades the appropriate inner or hub angles necessary for helical or similar twist, perpetuates itself during all 30 the stresses of protracted operation in flying, solely by its inherent elastic rigidity or set, at the angles, bends or curves imparted during manufacture or intentional adjustment. In order that such constancy 35 of shape under stress may exist there must be a relation between the thickness and width of the material and its elastic limit and other physical properties to insure constancy at the rate of rotation, thrust and the 40 other conditions specified by the particular flight duty for which the propeller is planned. I have found that for an absorption of 400 H. P., with a 10 foot propeller at 2000 R. P. M., and a pitch of 6 feet, a 45 thickness at the bends or twisted portions of about $\frac{3}{4}$ of an inch, with a width of 10 inches will suffice, when one uses material such as duralumin, or similar aluminum alloy, of extra tensile strength and elastic 50 limit. As the blades taper in thickness steadily to $\frac{1}{4}$ inch or $\frac{1}{8}$ inch, or less, at the tips 5 and 6, and also taper materially in width outwardly toward the tips, the resulting lightening in weight towards the tips 55 compensates for the increased radius, so that the blades may be calculated for a substantially uniform radial tension per unit of cross-section and the aggregate of such radial tensions at the bends or twists near 60 the axis region may be regulated not to exceed the amount which the bends or twists can sustain without straightening out under the duty for which the propeller is planned. With my improved propeller constructed as 65 herein shown and described, many flights

have been made by airplanes of usual type and dimensions for carrying several passengers and the propellers have been found to preserve their shape absolutely.

While the parts of a propeller blade near 70 the axis move relatively slowly in the path of rotation and furnish a relatively small fraction of the total propeller thrust, nevertheless they do so contribute, provided they are of the proper shape. In the wooden 75 propeller the exigencies of the material used, make it necessary to so expand in thickness the blade section up to 12 inches and even to 18 inches radius, that as may be readily noted by examination of drawings of conventional wooden blade sections, these portions are little better than clubs and cannot materially contribute to the thrust. By my construction of the entire propeller from a plate which need not exceed one inch in 80 thickness, at the thickest part, I am able to obtain effective thrust at points comparatively close to the axis of rotation, say for example, nine or twelve inches therefrom, and I thus add materially to the aggregate 85 efficiency of propellers.

Numerous flying tests of airplanes equipped with my propellers have demonstrated invariably the superior efficiency of my improved propeller and this is due mainly to 90 the unusually thin sharp blade sections beyond, say about thirty-six inch radius, and next to the unusually thin flat blade sections from about eighteen-inch radius to about ten-inch radius, the superiority of the sections from about eighteen-inches to about 95 thirty-six inches to the conventional sections being material but less marked, the tapering thickness being supplemented by the tapering width toward the tips. 100

In several of the constructions herein shown, I have indicated a nut 58, which turns on a thread on the propeller shaft 11, for the purpose of holding the propeller on the shaft and preventing its moving longitudinally thereon, while the key 17, locks the 105 two parts in fixed relation.

In the form of my propeller in which the central blade connecting portion is made flat and without bends or twists therein, as 110 indicated at 22, this flat portion provides an efficient and simple structure for mounting the propeller in place.

While the constructions referred to produce a continuation of the leading edge of 115 one blade with the trailing edge of the other, the invention is not limited to this relation of parts.

I wish to be understood as not limiting my inventions to the particular forms herein shown and described, as it is manifest that various modifications may be made in the different parts thereof, without, however, departing from the spirit of my invention. 120

Having thus described my invention, what I claim and desire to secure by Letters Patent is:

1. An aeronautical propeller having 5 blades formed of light-weight metal having a high degree of tensile strength and converging in cross-section toward the outer portions of the blades and depending partly but mainly upon centrifugal force for effective operation.
2. An aeronautical propeller having blades formed of light-weight metal, the propeller being relatively thin at its central portion and having a substantial width at 15 said central portion to provide the necessary rigidity to resist torque, and said propeller so converging in width toward the end portions of the blades as to provide the necessary relation of form to weight and which 20 blades depend substantially upon centrifugal force for effective operation.
3. An aeronautical propeller formed from a plate of light-weight metal in a single piece, the propeller having only the thickness 25 of the plate at its central portion and having a substantial width at said central portion such as to provide the necessary rigidity to resist torque, and said propeller so converging in thickness and in width toward 30 the tip portions of the blades as to provide the necessary relation of form to weight and which blades depend substantially upon centrifugal force for effective operation.
4. An aeronautical propeller formed of 35 light-weight metal, the propeller being relatively wide at its central portion to provide the necessary rigidity to resist torque, the said propeller converging progressively in cross-section toward the tip portions of the 40 blades to such a degree as to form relatively non-rigid end portions depending substantially upon the effect of centrifugal force to provide the necessary degree of rigidity for efficient operation.
5. An aeronautical propeller having 45 blades formed of duralumin or an alloy having substantially the physical characteristics thereof and said blades being of such thinness that the structural rigidity due to material and shape is not sufficient to produce the 50 total rigidity which is necessary to overcome the resistances in operation but has to be supplemented for an essential part by the kinetic rigidity resulting from the centrifugal 55 force.
6. An aeronautical propeller consisting of a single-piece forging of duralumin or an alloy having substantially the physical characteristics thereof and having a relatively substantial width at the central portion and the blades converging in width 60 toward the end portions.
7. An aeronautical propeller consisting of a single forged plate of duralumin or an alloy having substantially the physical 65 characteristics thereof and having a maximum thickness at its central portion substantially equivalent to the thickness of the plate and having a relatively substantial width at said central portion, and the blades 70 of the propeller converging in width and thickness toward the end portions thereof.
8. An aeronautical propeller constructed of light-weight metal and progressively decreasing in cross-section toward the outer 75 extremities of the blades to such an extent as to rely for stability against axial deflection substantially upon centrifugal force, and having a sufficient increase in width and thickness adjacent the axis of rotation 80 to provide stability against tangential deflection due to torque, said light-weight metal possessing an inherent rigidity which combined with the form of the blades provides stability of pitch.
9. An aeronautical propeller formed of light-weight metal with a thin cross-section throughout its length and progressively decreasing in cross-section toward the outer 85 extremities of the blades to provide a thin and sharp-edged construction and to rely for stability against axial deflection substantially upon centrifugal force, and being comparatively thin and wide at or near the axis to provide stability against tangential deflection due to torque of the drive-shaft, said light-weight metal having sufficient inherent rigidity when combined with the form of the blades to provide 90 stability of pitch when operating at high 95 rotative speeds.
10. An aeronautical propeller made from a single piece of light weight metal flat and thin throughout and with the blades united by a reversing formation and in 100 which the thickness and width of the axial zone is so adjusted to the physical properties of the material used and the stresses of service, that such central angle-reversing formation will persist without reinforcement during such service, and whose blades 105 depend partly but mainly upon centrifugal force for effective operation.
11. An aeronautical propeller having blades formed of an alloy of aluminum.
12. An aeronautical propeller having blades formed of duralumin.
13. An aeronautical propeller having blades formed of forged alloy of aluminum.
14. An aeronautical propeller provided with blades formed of light-weight metal having a relatively high tensile strength, said blades having relatively thin outer portions and increasing in cross-section away 120 from the outer portions and graded in width and cross-section only to the extent necessary to maintain the pitch twist of the blades.
15. An aeronautical propeller having

metal blades converging in width and thickness toward the outer ends, said blades possessing a substantial degree of rigidity but the degree of convergence being such as to require the supplemental stiffening action of centrifugal force for operation.

16. An aeronautical propeller having blades formed of light-weight metal having

a high degree of tensile strength, said blades converging in cross-section toward the outer portions thereof and depending upon centrifugal force for effective operation.

Signed at New York in the county of New York and State of New York this 21st day of June A. D. 1922.

SYLVANUS ALBERT REED.
